UNITED STATES PATENT OFFICE.

GEORGE H. SOLDANI, OF PONCA CITY, OKLAHOMA.

HEADLAMP-CONTROL DEVICE.

Application filed May 3, 1924. Serial No. 710,868.

To all whom it may concern:

Be it known that I, GEORGE H. SOLDANI, a citizen of the United States, residing at Ponca City, in the county of Kay and State 5 of Oklahoma, have invented new and useful Improvements in Headlamp-Control Devices, of which the following is a specification.

This invention relates to headlamps of 10 motor vehicles, and has for its object the provision of novel electromagnetically operated means for tilting the reflectors and bulbs of the lamps so that the light may be thrown downwardly onto the road way to 15 prevent glaring into the eyes of drivers of approaching cars.

Another object is the provision of a headlamp in which the reflector is pivotally mounted so that it may be moved without 20 changing the position of the lamp itself.

Yet another object is the provision of a structure of this character which requires no manual manipulation on the part of the operator other than the closing of a switch, 25 means being furthermore provided for holding the parts in either selected position.

An additional object is the provision of a 30 device of this character which will be simple and inexpensive in manufacture, easy to install, simple to operate, positive in action, efficient and durable in service and a general improvement in the art.

With the above and other objects and advantages in view the invention consists in 35 the details of construction to be hereinafter more fully described and claimed and illustrated in the accompanying drawings, in which:

Figure 1 is a vertical section through the 40 forward portion of an automobile showing an elevation of my headlamp control device in position.

Figure 2 is a longitudinal section on a 45 larger scale through the lamp and a portion of the operating mechanism.

Figure 3 is a vertical section through the casing containing the electromagnets,

Figure 4 is a horizontal section through the casing showing a plan view of the operating mechanism,

Figure 5 is a diagram of the electric circuit.

Referring more particularly to the drawings the letter A designates the forward 50 portion of an automobile, B represents the radiator, C a headlamp mounted in a bracket

D. In carrying out my invention I provide the lamp with a reflector 10 which is pivotally mounted within the lamp casing so as to be capable of vertical swinging movement. At the back of this reflector is a sleeve 11 carried by a depending arm 12 for a purpose to be described. Slidable within the sleeve is a socket 13 which carries the bulb 14 and which is adjustable for focusing the light. The adjusting means is here shown as consisting of an angular bracket 15 carried by the sleeve 11 and slidably engaged by a bracket 16 on the socket 13. An adjusting screw 17 passes through the bracket 16 and is journaled in the ends of the bracket 15. By turning the screw one way or the other it is apparent that the socket 13 and consequently the bulb 14 may be moved longitudinally to focus the light.

Mounted within the hood of the car and secured on any convenient portion of the engine, timing gear, frame or anywhere else, is a casing designated broadly by the numeral 18 and including a stationary base 80 portion 19 and a cover portion 20. Located within this casing are two electromagnets 21 arranged in superposed relation with their cores 22 spaced apart. Any suitable brackets 23 are provided for mounting these 85 magnets. Journaled through the opposite sides of the casing 18 is a rock shaft 24 equipped with an arm 25 carrying an armature 26 positioned between and adapted to be attracted by the magnets 21. Secured 90 upon the ends of this rock shaft are arms 27 which are connected at 28 with forwardly extending rods 29 which connect at 30 with the depending arms 12 of the reflector tilting means. These rods 29 are formed of 95 sections 31 and 32 connected by a turn buckle 33 so that adjustment may be made for maintaining the reflectors of the lamps in proper normal position.

The control device consists of any suitable 100 switches connected in circuit with the magnets and with a source of current. Push buttons or a single switch arm movable over two contacts may be used, as preferred and there is no restriction in this respect. However for the sake of illustration, I have shown a switch device including a pivoted arm 33 connected by a wire 34 with one pole of a source of current 35 and movable selectively to engage either of a pair of contacts 36 and 37, the former of which is connected 105 by a wire 38 with the upper magnet 21 and

the lower of which is connected by a wire 39 with the lower magnet. The coils of the two magnets are connected with the source of current by a return wire 40.

- 5 In the operation, it will be apparent that as the operator moves the switch arm 33 into engagement with the contact 36, the upper electromagnet 21 will be energized and will swing the arm 25 upwardly, rocking the 10 shaft 24, swinging the arms 27 forwardly and moving the rods 29 forwardly, all of which results in moving the reflectors 10 into their uppermost or normal straight ahead position. The numeral 41 represents a 15 spring catch device which will hold the reflectors in this position without it being necessary to maintain a constant current flow through the upper magnet. When approaching another car or when passing 20 through a town where bright lights are prohibited, the operator may avoid the blinding effect of his headlights by moving the switch arm 33 into engagement with the contact 37 for energizing the lower magnet 21. When 25 this is done the arm 25 swings downwardly and the arms 27 swing rearwardly, pulling the rods 29 rearwardly and tilting the reflectors downwardly, the spring device 41 operating to retain the reflectors in this position until they are returned to normal position by energization of the upper magnet.

From the foregoing description and a study of the drawings it will be apparent that I have thus provided a simple, inexpensive and easily operated device for the purpose specified which will be a great safe guard to the motoring public and which will avoid any necessity for the employment of special lenses or other dimming devices.

40 While I have shown and described the preferred embodiment of my invention it is of course to be understood that I reserve the right to make such changes in the form, con-

struction and arrangement of parts as will not depart from the spirit of the invention 45 or the scope of the subjoined claims.

I claim:

1. In an apparatus of the character described, headlamps mounted upon a vehicle, vertically tiltably mounted reflectors within the headlamps, depending arms extending from the reflectors, a casing located beneath the hood of the vehicle, a rock shaft journaled through said casing and having crank arms connected with said first named arms, 55 an arm on the rock shaft located within the casing and carrying an armature, a spring within the casing, and a pair of electromagnets mounted within said frame in vertically spaced relation and having cores located 60 above and below the armature whereby upon energization of a selected electromagnet the last named arm will be swung to rock the shaft and tilt the reflectors.

2. In an apparatus of the character described, headlamps mounted upon a vehicle, vertically tiltably mounted reflectors within the headlamps, depending arms extending from the reflectors, a casing located beneath the hood of the vehicle, a rock shaft journaled through said casing and having crank arms connected with said first named arms, 70 an arm on the rock shaft located within the casing and carrying an armature, a frame within the casing, and a pair of electromagnets mounted within said frame in vertically spaced relation and having their cores located above and below the armature whereby upon energization of a selected electromagnet the last named arm will be swung to rock 75 said shaft and tilt the reflectors and a spring connected with the frame and the last named arm for normally maintaining the parts in normal position.

In testimony whereof I affix my signature.

GEORGE H. SOLDANI.
